UNITED STATES PATENT OFFICE

162,188

BABY CHAIR

Anthony J. Leffler, deceased, late of Penn Township, Allegheny County, Pa., by John J. Leffler, Vincent Leffler, and Anthony Leffler, executors, Penn Township, Allegheny County, Pa.

Application November 29, 1949, Serial No. 6,308

Term of patent 7 years

(Cl. D15—1)

To all whom it may concern:

Be it known that Anthony J. Leffler, deceased, late a citizen of the United States of America, residing at Penn Township, in the county of Allegheny and State of Pennsylvania, had invented a new, original, and ornamental Design for a Baby Chair, of which the following is a specification, reference being had to the accompanying drawing, forming part thereof.

What is claimed is:

The ornamental design for a baby chair, as shown.

JOHN J. LEFFLER,
VINCENT LEFFLER,
ANTHONY LEFFLER,

Executors of the Estate of Anthony J. Leffler, Deceased.
